SHEET RECEIVING RECEPTACLE AND
STACKER

Paul A. Gollnick and Kurt Emde, Chicago, Ill.,
assignors to Selectograph Company, Chicago,
Ill., a corporation of Illinois

Application June 28, 1934, Serial No. 732,762

3 Claims. (Cl. 271—86)

This invention relates generally to receiving receptacles for sheet material but the receptacles to which this invention is applied are particularly adapted for use in connection with printing machines, such as duplicators or addressing machines, for stacking the postcards, envelopes, folders, blotters and similar sheet material which is fed flatwise through the machine.

In duplicators heretofore in use, the printed sheets have been ejected flatwise into a receiving container in which they were stacked one on top of the other. Such method of stacking is very objectionable because the newly inked surfaces smudge the contacting surfaces of adjacent sheets, due to the weight of the sheets which are stacked flatwise.

To obviate such smearing of the sheets, some of the duplicators heretofore in use have been provided with means for interleaving the stack with blank sheets, but this has materially increased the cost of the machines and the cost of operation.

The main objects of this invention are to provide an improved receiving container for receiving the sheets which are ejected from printing machines and the like; and to provide improved means for stacking the sheets on edge in said container to overcome the smudging caused by flatwise stacking of the sheets and to obviate the expense and trouble incident to interleaving.

An illustrative embodiment of this invention is shown in the accompanying drawings, wherein:

Fig. 1 is a side elevation of an improved receptacle attached to the end of a duplicator.

Fig. 2 is a perspective of the receptacle.

Fig. 3 is an enlarged transverse section, taken on the line 3—3 of Fig. 1.

A receptacle and stacker embodying this invention may be used in connection with numerous types of printing mechanisms. In the drawings, for the purposes of illustration, we have disclosed part of a duplicator which is similar to the one described and claimed in our copending application Serial No. 729,846, filed June 9, 1934.

In the form shown, the duplicator comprises a frame 1 having a horizontal guideway 2 along which are fed postcards, folders, forms, or other sheets 3 which pass one at a time between a duplicator drum 4 and a platen roller 5. The drum 4 is journaled on the frame 1 and is provided with the usual operating crank 6. The platen roller 5 is located below the path of the sheets for pressing each sheet into contact with the usual stencil 7 which is carried by the drum.

Inasmuch as the specific structural details of the machine have no bearing upon the receiving container, we have shown and described only those portions of the duplicator which will be of assistance in describing the container to which this invention is applied.

When the sheets are passing through the duplicator they are disposed horizontally and, after being ejected by the drum 4, they drop flatwise to the improved receiving container or tray 8.

In the form shown, the improved sheet receiving container or tray is of a duplex type and comprises a central partition 9 of substantially inverted V-shape having its lower portions bent outwardly to form a pair of curved shelves 10. The partition 9 straddles a channel bar 11 to which it is rigidly secured by any suitable fastening means. One end of the channel bar 11 projects beyond one end of the partition 9 and has a pair of notches 12 for engaging a horizontal rod 13 which forms a part of the machine frame 1. This connection between the tray and the machine permits the tray to be shifted laterally relative to the machine for distributing the sheets on both sides of the partition as hereinafter described. The construction is such that, when the tray is attached to the machine, the ridge of the partition 9 is slightly inclined, with its highest end located adjacent the machine and slightly below the plane of the sheet guideway.

Straddling the ridge of the partition 9, is an end plate 14, which is adjustably secured to the partition by a set-screw 15 which permits the end plate to be adjusted longitudinally of the ridge and form a stop for sheets of various lengths.

In operation, the tray is placed so as to position the ridge of the partition 9 to one side of the longitudinal center line of the ejected sheet. When the sheet is ejected by the duplicator drum, the sheet falls flatwise so as to strike the ridge of the tray and it is thereby turned on edge so as to drop onto one of the curved shelves 10. Due to the curvature of the shelves, the sheets become stacked in fan shape, with the lower edges thereof spaced from one another, thereby eliminating all possibility of smudging.

When one of the shelves 10 has been filled, the tray is shifted laterally on the rod 13 to a position which will cause the ejected sheets to thereafter drop onto the other shelf.

Although but one specific embodiment of this invention has been herein shown and described, it will be understood that certain details of the construction shown may be varied without de-

parting from the spirit of the invention as defined by the following claims.

We claim as our invention:

- 5 1. In a device of the class described, the combination with a guideway from which sheets are successively ejected in a substantially horizontal plane, of a duplex tray for receiving and automatically stacking the sheets on edge and substantially out of contact with each other except at their top edges, comprising an inverted V-shaped partition member the top edge or ridge of which extends forwardly from said guideway, and outwardly and upwardly curved shelves respectively continuous with the lower edges of the 10 limbs of said partition member onto which the sheets fall edge foremost, the concave upper faces of said shelves automatically spacing the lower edges of the sheets as the latter fall thereon, and means for supporting said tray with capacity for 15 adjustment laterally to bring the top edge or ridge of said partition to one side or the other of the transverse center of said guideway.
- 20 2. In a device of the class described, the combination with a guideway from which sheets are successively ejected in a substantially horizontal plane, of a duplex tray for receiving and automatically stacking the sheets on edge and substantially out of contact with each other except at their top edges, comprising an inverted V-shaped rectangular partition member, the top edge or ridge of which extends forwardly from said guideway, outwardly and upwardly curved shelves respectively continuous with the lower edges of the limbs of said partition member onto 25 which the sheets fall edge foremost, the concave upper faces of said shelves automatically spacing the lower edges of said sheets as the latter fall 30

thereon, means for supporting said tray in a downwardly and forwardly inclined position with capacity for adjustment laterally to bring the top edge or ridge of said partition to one side or the other of the transverse center of said guideway, 5 and a stop member for the sheets straddling the top edge of said partition.

3. In a device of the class described, the combination with a printing machine frame having a guideway from which printed sheets are successively ejected in a substantially horizontal plane, and a transverse horizontal rod underlying the forward end of said guideway, of a duplex tray for receiving and automatically stacking the sheets on edge and substantially out of contact with each other except at their top edges, comprising an inverted V-shaped partition member the top edge or ridge of which extends forwardly from said guideway, outwardly and upwardly curved shelves respectively continuous with the lower edges of the limbs of said partition member onto which the sheets fall edge foremost, the concave upper faces of said shelves automatically spacing the lower edges of the sheets as the latter fall thereon, means for supporting said tray in a downwardly and forwardly inclined position with capacity of lateral adjustment to bring the top edge or ridge of said partition to one side or the other of the transverse center of said guideway comprising a bar extending between and attached to the limbs 30 of said partition and having a notched rear end slidably engaged with said rod, and a stop member for the sheets straddling the top edge of said partition.
